J. C. WELAGE

PILE DELIVERY FOR PRINTING PRESSES

Filed Sept. 27, 1924

FIG. 1

FIG. 2.

INVENTOR
Joseph C. Welage
By John W. Trehli
ATTORNEY.

UNITED STATES PATENT OFFICE.

JOSEPH C. WELAGE, OF CINCINNATI, OHIO.

PILE DELIVERY FOR PRINTING PRESSES.

Application filed September 27, 1924. Serial No. 740,320.

To all whom it may concern:

Be it known that I, JOSEPH C. WELAGE, a citizen of the United States, residing at the city of Cincinnati, in the county of 5 Hamilton and State of Ohio, have invented certain new and useful Improvements in Pile Deliveries for Printing Presses, of which the following is a specification.

My invention relates to a pile delivery 10 means for printing presses and applies particularly to the pile or stack of circulars, cards, papers, sheets, and the like, after they have been singly piled one on top of the other by the delivery fly of the press, 15 and consists essentially in means for keeping each sheet delivered by the fly onto the pile, in alignment and keeping the corners of the delivered sheets from turning over, especially at the corners thereof.

It is a well known fact that on account 20 of quick operation of the delivery fly and the parts of the printing press adjacent thereto, and from drafts and air, the upper sheet or sheets of the pile having a tendency 25 to turn up, especially at the corners, thus interfering with the proper alignment of the pile of sheets, and turning over of the corners, marring the sheet and thus causing great inconvenience and annoyance.

By the use of my attachment these objections are overcome, inasmuch as I provide guard fingers, which, when the delivery fly is receiving another sheet to place upon the top of the pile, are in touch with the last delivered sheet and hold it until the delivery 35 fly is ready to place another sheet upon the pile, the guard fingers moving out of the way until said sheet is placed upon the pile and then again holding this sheet until an-

other is ready to be delivered by the fly.

My attachment is simple, practical and efficient, cheap of manufacture and can readily be applied to the printing presses and possesses a high degree of utility.

The various features and advantages of my invention will readily become apparent from reading the following specification.

In the accompanying drawing forming part of this specification:

Fig. 1, is a plan view of my invention, 50 Fig. 2, is a section taken on line 2—2 of Fig. 1, and

Fig. 3, is a section taken on line 3—3 of Fig. 1.

In the drawing, 1, represents the rear jogger, and to the same I connect the brackets

2, and in these brackets I place the shaft 3 which carries the guard fingers 4 securely fastened thereto.

Securely fastened to the shaft 3, I provide 60 an adjustment lever 5 which allows shaft 3 to return to a predetermined point.

Loosely mounted on shaft 3, I provide a lever 6 which carries a pawl 7 mounted on the screw stud 8. This pawl 7 engages with 65 a one tooth ratchet 9, which is also securely mounted to the shaft 3; a coil spring 10 which is mounted on the screw stud 8 is for the purpose of holding into engagement the pawl 7 into ratchet 9. A coil spring 12 is 70 mounted on the shaft 3 and has one end fastened to said shaft at point 13 and the other end is connected to one of the brackets 2. This spring causes the shaft 3 to return quickly to its normal position when the pawl 75 7 is disengaged when at its extreme outward position, as will be hereinafter pointed out.

At the point 14 on the lever 6 I fasten one end of a coil spring 15, the other end of which is connected at the point 16 to the 80 belt 17, which belt is fastened to a cam 18 which is mounted on a rock or cam shaft 19 of the printing press. A chain 20 has one end fastened to the spring 15 at point 21 and the other end to the pawl 7 at the 85 point 22. A spring 23 mounted on the shaft 3 has one end fastened to one of the brackets 2 and the other end of same spring is fastened to the stud screw 8 at the point 24, which allows the lever 6 to return to its 90 normal position as shown in Figs. 1 and 2, or when the guard fingers 4 are down in touch with the pile of paper.

An adjusting screw 25 is mounted in a plate 26, for the purpose of adjusting the return travel of the lever 6 and an adjusting screw 26 is for the purpose of adjusting the return travel of the fingers 4 through the agency of the adjustment lever 5.

The guard fingers 4 on the shaft 3 are 100 raised in position as shown in Fig. 3, in dotted lines, and out of the path of the sheet being delivered by the delivery fly, in the following manner: As cam shaft 19 of the printing press rocks, the cam 18 draws forward on belt 17 to the spring 15, to lever 6 causing said lever to travel in said direction, the lever 6 carrying pawl 7, which engages ratchet 9, said ratchet being tight on shaft 3 causing said shaft to revolve to the 105 position shown in Fig. 3, in dotted lines, carrying with it the guard fingers 4, (in

this position the fingers are out of the path of the fly delivery). The fingers remain in this position for a very short time and as the next sheet is placed on the pile by the fly delivery, then the pawl 7 is released from the ratchet 9 by reason of chain 20 being pulled to its limit of length, thus disengaging said pawl 7, which allows the spring 12 to act and return the fingers quickly to the position shown in Figs. 2 and 3, that is, down on the pile of sheets.

The adjusting lever 5 on shaft 3 will allow fingers 4 to return to the adjusted position obtained by the adjusting screw 26 and as the rock or cam shaft 19 of the printing press returns to its previous position allows the lever 6 with its pawl 7 to return to original position and again become engaged with the ratchet 9, which is also securely mounted to shaft 3. The spring 10 causes the pawl 7 to bear down and properly engage in said ratchet 9, as the chain 20 becomes slack, which allows the pawl 7 to engage with said ratchet.

25 I may use any number of guard fingers found necessary, and in the present instance I use four, the two outer guard fingers being used being wide sheets and the two inner guard fingers are used for sheets which are not of great width, although preferably I use them all with wide sheets.

While I have described one specific and preferred method of carrying my invention into effect, it will be readily understood that I may make changes and modifications therein which will fall within the scope of this specification and still fall within the scope of my invention.

What I claim as new and my invention 40 and desire to secure by Letters Patent is:—

1. In an attachment for printing presses of the character described, in combination with the rear jogger and the cam or fly shaft of the said press and the pile delivery mechanism, of a shaft supported on the rear jogger, guard fingers, attached to said shaft,

means for oscillating said shaft, said guard fingers moving with said shaft as the same is oscillated, to bring said guard fingers down upon the pile as each sheet is delivered by the fly delivery mechanism, and raising said fingers off of said pile at a predetermined time, to allow the fly delivery mechanism to deliver the next sheet.

2. In an attachment for printing presses 55 of the character described, in combination with the rear jogger and the cam or fly shaft of the said press and the pile delivery mechanism, of a shaft supported on the rear jogger, guard fingers, attached to said shaft, means for oscillating said shaft, said guard fingers moving with said shaft as the same is oscillated, to bring said guard fingers down upon the pile as each sheet is delivered by the fly delivery mechanism, 60 and raising said fingers off of said pile at a predetermined time, to allow the fly delivery mechanism to deliver the next sheet, and means connected with the oscillated shaft, carrying the guard fingers for adjusting same in its oscillating movement.

3. In an attachment for printing presses of the character described, in combination with the rear jogger and the cam or fly shaft of the said press and the pile delivery 75 mechanism, of a shaft supported on the rear jogger, guard fingers, attached to said shaft, means for oscillating said shaft, said guard fingers moving with said shaft as the same is oscillated, to bring said guard fingers 80 down upon the pile as each sheet is delivered by the fly delivery mechanism, and raising said fingers off of said pile at a predetermined time, to allow the fly delivery mechanism to deliver the next sheet, the raising 85 and lowering of the guard fingers regulated through a cam or fly shaft and intermediate mechanism between said cam and the shaft.

In testimony whereof, I affix my signature at Cincinnati, Ohio, this 18th day of September, 1924.

JOSEPH C. WELAGE.
